UNITED STATES PATENT OFFICE.

SAMUEL BUCHSBAUM, OF CHICAGO, ILLINOIS.

DESIGN FOR A BELT-BUCKLE FRAME.

60,850.

Specification for Design.

Patented Apr. 18, 1922.

Application filed July 11, 1921. Serial No. 483,972. Term of patent 3½ years.

To all whom it may concern:

Be it known that I, SAMUEL BUCHSBAUM, a citizen of the United States, residing at Chicago, in the county of Cook and State of Illinois, have invented a new, original, and ornamental Design for Belt-Buckle Frames, of which the following is a specification, reference being had to the accompanying drawing, forming part thereof.

Fig. 1 is a front face view of a belt buckle frame showing my new design; and

Fig. 2 is a rear face view thereof.

I claim:

The ornamental design for a belt buckle frame, as shown.

SAMUEL BUCHSBAUM.
